ICE BUCKET

Carlo Samtambrogio, Milan, Italy, assignor to L. Baflin & Son, Inc., New York, N.Y.

Filed Mar. 28, 1968, Ser. No. 11,163

Term of patent 14 years

Int. Cl. D7—01

U.S. Cl. D44—1

FIG. 1

FIG. 2

FIG. 3

FIG. 4

FIG. 6

FIG. 5

FIG. 1 is a perspective view of an ice bucket showing my new design, with the cover in open position;

FIG. 2 is an enlarged scaled front elevational view with the cover in closed position;

FIG. 3 is a rear elevational view thereof;

FIG. 4 is a right side elevational view;

FIG. 5 is a top plan view; and

FIG. 6 is a bottom plan view.

I claim:

The ornamental design for an ice bucket, as shown.
